Attn: Attn:

UNITED STATES PATENT OFFICE.

WILLIAM C. CODMAN, OF PROVIDENCE, RHODE ISLAND, ASSIGNOR TO THE GORHAM MANUFACTURING COMPANY, OF SAME PLACE.

DESIGN FOR A SPOON.

SPECIFICATION forming part of Design No. 27,088, dated May 25, 1897.

Application filed April 6, 1897. Serial No. 631,022. Term of patent 7 years.

To all whom it may concern:

Be it known that I, WILLIAM C. CODMAN, of Providence, in the county of Providence and State of Rhode Island, have invented and produced a new and original Design for Spoons; and I hereby declare that the following is a full, clear, and exact description of the same, reference being had to the accompanying drawings, forming part thereof.

10 Figure 1 is a view of the obverse side of a spoon, showing my design. Fig. 2 is a view of the reverse side of the spoon.

The leading features of my design consist in the raised foliations extending from the 15 edge of the handle inward, terminating at the upper end of the spoon in a draped space, and the representation of toys on the obverse side of the handle and the bowl, more fully described hereinafter.

20 In the drawings, A indicates the bowl of the spoon; B, the neck, and C the blade, of the handle. On both the obverse and reverse sides of the spoon, at the junction of the handle with the bowl of the spoon, the foliation 25 d extends from the narrow neck B over a portion of the bowl A. From the upper part of the neck B extends the raised foliated stem e between the marginal raised stems ff, which,

extending upward, form the succession of inwardly-inclined leaves g. The marginal stem 30 extends upward above the foliations gg under the festooned drapery hh, which ornaments the upper end of the handle. On the obverse side the space between the marginal 35 ornamentalations has at the upper end the representation of an infant's face i and below this an end view of the cradle k, from which extends a line connecting the representations of toys along the center of the handle. From the foliated end d of the handle, within the 40 bowl A, a ribbon bow connects with the representation of a series of toys.

When viewed as a whole, the design conveys to the eye the appearance of a nursery-spoon.

Having thus described my invention, I claim as new and desire to secure by Letters Patent—

The design for a spoon herein shown and described.

In witness whereof I have hereunto set my hand.

WILLIAM C. CODMAN.
